6 Claims. (Cl. 140—113)

ABSTRACT OF THE DISCLOSURE

A self-adjusting machine for closing wirebound boxes with interengaged loop fasteners, having movable actuator assemblies with loop bending members resiliently mounted thereon on pivotal axes located so that said loop bending members move first downwardly to engage the top of the box, then forwardly to the closing corner of the box, then downwardly along the front of the box to bend the outer loop downwardly around said corner and the inner loop around the outer loop and downwardly against the side of the box.

This invention relates to a machine for completing the assembly of wirebound boxes (which term is used herein to include crates and other types of wirebound containers), and particularly wirebound boxes of the type known in the trade as "Du-All" boxes.

Such boxes are formed from wirebound box blanks having three side sections and one end-forming section foldably secured together by binding wires extending longitudinally of the box blank and secured to the several sections by staples driven through the face material and into the reinforcing cleats which extend longitudinally along the lateral edges of each of the sections. When the box blank is folded around to set up the box, the three side sections form the front, bottom and rear sides of the box, while the cleats at each end of the end-forming section complete a rectangular cleat framework at each end of the box, and the end-forming panels of face material stapled to said cleats are bent downwardly to close the ends of the box, thereby forming a five-sided, open-topped box which may be subsequently closed by a separate lid. The ends of each of the outside binding wires are provided with loop fasteners, and when the box is set up, the two loops at the opposite ends of each of the binding wires come into opposition with one another at the closing corner of the box. The loops on the front section of the box, being somewhat narrower than the loops on the end-forming section of the box, are inserted through the latter and bent downwardly against the front of the box to hold the box in properly assembled relation.

The present invention provides a machine for receiving boxes of this and similar types which have been partially assembled by folding the box blank and threading the inner loop fasteners on the front side of the box through the mating outer loop fasteners on the top or end-forming section of the box. The machine is adapted to hold the box in a fixed position while squaring its sides and pressing the cooperating ends of the rectangular cleat framework tightly together, and then close the loop fasteners by bending the outer loops around the closing corner of the box and downwardly against its front side of the box and bending the inner loops around the outer loops and downwardly against the front side of the box.

Two embodiments of the machine are described and shown herein. In the first of these, the motive power is supplied by a foot treadle. In the second embodiment, power is supplied by an electric motor which also drives an intermittently operating conveyor which transports the boxes successively into proper position at the box assembling station within the machine, and then transports the assembled boxes out of the machine.

2

In the drawings:

FIGURE 1 is an end elevational view of a foot-powered machine embodying features of the invention, with the box-squaring and loop-bending elements of the machine being shown in full lines in the retracted position they occupy between box-assembling operations and in broken lines in the positions they assume at the completion of a box-assembling operation.

FIGURE 2 is a side elevation of the machine shown in FIGURE 1, as viewed from the side appearing at the left in that figure, showing the threaded fastener loops at the closing corner of the box, in position to be operated upon by the loop-bending elements of the machine.

FIGURE 3 is an enlarged fragmentary view of the mechanism appearing in the upper portion of FIGURE 1, showing in full lines and broken lines the loop-bending elements and associated parts in successive stages of a loop-bending operation.

FIGURE 4 is a fragmentary view of a portion of the mechanism shown in FIGURE 3, on the same scale as FIGURE 3, taken in the direction indicated by arrows 4—4 in that figure.

FIGURE 5 is an isometric view of the type of five-sided, open-topped wirebound box upon which the machine is particularly adapted to operate, with its fastener loops threaded in preparation for closure by the machine.

FIGURE 6 is an enlarged, fragmentary isometric view of a corner of the box after the fastener loops have been closed.

FIGURE 7 is a side elevational view of a motor-driven machine, constituting an alternative embodiment of the invention.

FIGURE 8 is a fragmentary elevational view, at enlarged scale, of the opposite side of the machine of FIGURE 7.

FIGURE 9 is an end elevational view of the machine, on the same scale as FIGURE 8, as viewed from the end appearing at the right in that figure.

FIGURE 10 is a fragmentary vertical sectional view, at enlarged scale, taken on the line 10—10 of FIGURE 9.

As may be seen in FIGURES 1 and 2, the foot-operated machine is supported on a framework including corner posts 2 at its rear side R and somewhat smaller and shorter corner posts 4 at its front side F, these being cross-braced in their central portions by horizontal members 6 and at their lower ends by smaller horizontal members 8. The two rear corner posts 2 are cross-braced centrally by a horizontally extending angle member 10 whose horizontal flange 12 is secured to the upper surfaces of the horizontal members 6 and whose vertical flange is secured to the inner edges of the rear corner posts 2, while their lower ends are cross-braced by a vertically positioned plate 14.

Adjustably supported on the rear flanges of the corner posts 4 at the front side of the machine are a pair of vertically spaced, horizontally extending bracing rods 16 which engage the adjacent side of the box during the loop-bending operation. The horizontal members 6 pivotally support the lower ends of a generally vertically positioned, H-shaped presser frame 18 formed of angular side members 20 having secured near their lower ends a pair of block members 22 which are pivotally mounted on a horizontal rod 24 extending between the horizontal members 6 and secured thereto by bolts 26. The side members 20 of the H-shaped presser frame have secured to their inner flanges a pair of blocks 30 to whose outer faces are secured the edges of the flanges of an angle member 32, whose inclined upper surface is positioned to engage the adjacent lower corner of the box simultaneously as the front side of the box is engaged by a presser bar 35.

spaced thereabove and adjustably fastened to the inner flanges of the side members 20. As subsequently described, at the commencement of the loop-bending operation, the H-shaped presser frame is rocked inwardly so that the presser bar 35 and angle member 32 respectively engage the front side and lower corner of the box and press its rear side against the bracing rods 16, thereby squaring the box and holding it in position for the loop-bending operation.

Secured to the upper surface of horizontal members 6 by bolts 38 are a pair of spaced, horizontally extending angle members between which extend a pair of horizontal rollers 40, which rotate freely on shafts 42 secured to the vertical flanges 44 of rails 36. The rollers 40 not only facilitate movement of the containers into and out of the machine but also serve to properly position the box longitudinally for the loop-bending operation since, as shown at P in FIGURE 2, they are so spaced that the lower corners of the box can fit between them to allow the box to rest on the upper edges of the vertical flanges of the rails 36.

Secured to and projecting upwardly from the upper ends of the side members 20 are extension rails 46 having at their upper ends cap members 48 with downwardly inclined projecting ends. A short distance below the cap members 48, the edges of the extension rails 46 are provided with inclined cam surfaces 50, shown more clearly in FIGURE 3, which cooperate with an actuator assembly now to be described.

As shown in FIGURES 1, 2, and 3, and particularly FIGURE 3, the rear corner posts 2 support at their inner faces near their upper ends a pair of bearing members 52 in which the ends of a horizontal shaft 54 are journaled. Fixed on shaft 54 adjacent the bearing members 52 are a pair of arms 56 which extend forwardly and upwardly and which at their central portions have openings through which are supported opposite ends of a horizontal rod 55 by means of screws 68. Rotatably mounted thereon is a pair of rollers 64 which are held endwise by washers 66 and screws 68. The rollers 64 are in alignment with the aforementioned inclined cam surfaces 50 of the extension rails 46. At their outer ends, the arms 56 support another horizontal shaft 70, which extends between their inner faces and is secured to the arms 56 by screws 72 extending therethrough and threaded into the ends of the shaft 70. Rockably mounted at each end of shaft 70 are the loop fastener bending assemblies. Since the two assemblies of this illustrative machine are substantially similar, it will suffice to describe only one of them. As shown in FIGURES 3 and 4, the loop fastener bending assembly comprises a body member 74 rotatably mounted on the shaft 70 adjacent the inner face of the arm 56 and held endwise by a collar 76. As best shown in FIGURE 4, the body member 74 has a projecting therefrom an integral arm 78 whose front end is horizontally beveled and has secured to it one of the faces of a plate member 80, whose bottom edge is vertically beveled, so that the generally horizontal loop-engaging bar 82 secured thereto is slightly inclined inwardly and downwardly relative to the closing corner of the box for a purpose hereinafter described. Projecting from the opposite side of body member 74 is an integral, upwardly projecting finger 84 to which is hooked one end of a tension spring 86 whose other end is hooked about a screw 88 threaded into and through a tab 90 projecting inwardly from the upper edge of arm 56. Secured to the lower edge of arm 56 opposite tab 90 is another tab 92 which serves as the lower stop for the head of a bolt 94 threaded through arm 78 and held fixed by a lock nut 96. The upper stop for the head of the bolt 95 is provided by the lower end of the bolt 88, which is adjusted and secured by a lock nut 98 to permit arm 78 to move through a short angular arc during a loop-bending operation, thereby allowing limited movement of the loop-engaging bar 82 relative

to the arm 56, as indicated in full and broken lines in FIGURE 3.

Referring again to FIGURES 1 and 2, a foot treadle 100 having a foot plate 102 secured to the beveled end 104 portions of the upper faces of a pair of spaced arms 104 whose opposite ends are secured to a horizontal shaft 106 whose ends are journaled in bearings 108 mounted at the inner face of the aforementioned transverse plate 14. The arms 104 are centrally joined by a horizontal rod 110 which has rotatably mounted at its center the adjustable end 62 of a connecting rod 60 whose upper end is rotatably mounted on the aforementioned horizontal rod 55. Thus a driving connection is provided between the foot treadle 100 and the actuator assembly for the box-squaring and loop-bending elements.

The foot treadle 100 is normally held in raised position, in which it is shown in FIGURES 1 and 2, by a pair of tension springs 114 whose upper ends are hooked through openings near the lower ends of the inwardly projecting flanges of the side members 20 of the presser frame 18, and whose lower ends are hooked about bolts 116 threaded into the ends of rod 110. The tension springs 114 further serve to maintain the pivotally mounted presser frame 18 and its associated elements in their normal, generally vertical position indicated by full lines L in FIGURE 1, and also, through connecting rod 60, to maintain the arms 56 of the actuator assembly in their upper position, shown in that figure, in which the rollers 64 engage the underside of the downwardly inclined projecting ends of the cap members 48. To absorb the shock of an abrupt return of the actuator assembly to this upper position, for example due to the slippage of the operator's foot off of the treadle 100, there is provided a tension spring 118 whose upper end is hooked to a strap 120 pivotally attached to the shaft 55 and whose lower end is hooked through an eye at the upper end of a vertical rod 122 whose lower end is threaded in the horizontal flange 12 of the angle member 10 and secured by lock nuts 124.

FIGURE 5 shows a five-sided, open topped box of the general type with which the present invention is particularly adapted to be used, although it also may be used for assembling or closing other types of containers including conventional six-sided wirebound containers. The box of FIGURE 5 is shown with the inner loop fasteners A at its front side A₁ threaded through the outer loop fasteners B of the top side B₁ and bent outwardly to the slight extent necessary to maintain the box in folded form. The box-folding and partial assembly operation is performed at a station remote from the machine, and the box is conveyed to the machine by means of a roller conveyor or the like, as indicated at D in FIGURE 2. The operator of the machine guides the box over the roller 40 at the input end of the machine and to a point where the bottom of the box rests between the rollers 40, as shown at P in FIGURE 2. The operator then steps on the treadle 100, forcing it downwardly against the resistance of the tension springs 114, pulling down the connecting rod 60 and rocking the actuator assembly downwardly. During the first portion of such movement, the rollers 64 move inwardly against the adjacent edges of the extension plates 46, thereby causing the H-shaped frame 18 and its associated elements to rock counterclockwise to the position indicated by broken lines L₁ in FIGURE 1. This movement causes the inclined upper surface 34 of angle member 32 and the presser bar 35 respectively to engage the adjacent bottom corner A₂ and front face A₁ of the box, clamping the box against the bracing rods 16 at the opposite side, thus squaring the box and holding it in position for the loop-bending operation.

As the arms 56 continue downwardly, as indicated by the arrow G in FIGURE 3, the loop-engaging bars 82 move downwardly into engagement with the top of the box adjacent the rear side of the inner fastener loop A, pressing the ends of the cleats at the closing corner of the box tightly together. As the downward movement of the arms 56 continues, the arms 78 rotate counterclock-

wise relative to the arms 56, against the resistance of the springs 86. The arms 78 are so shaped and their axes of rotation are so located that the arc of movement of the loop-engaging bars 82 has an upwardly directed vertical component and an outwardly directed horizontal component, so that their resultant movement, as indicated by the arrow H, is generally horizontal until the bars 82 clear the corner of the box, whereupon the further pivotal movement of the arms 78 is stopped by engagement of the heads of bolts 94 with the lower ends of bolts 88. As the downward movement of the actuator assembly continues, the loop-engaging bars 82 move generally downwardly in fixed relation with the arms 56, as indicated by arrow J in FIGURE 3. This results first in bending the outer loops B downwardly against the front of the box and then bending the inner loops A downwardly around the bights of the outer loops and against the front of the box, thus tightly closing the corner of the box, as shown in FIGURE 6. The aforementioned inward and downward inclination of the loop engaging bars 82 serves to urge the inner loops A inwardly of the outside binding wires and into engagement with the face material on the front of the box.

The release of the foot treadle 162 allows the springs 114 and 85 to return all of the parts to their original retracted positions out of engagement with the assembled box, so that it may be removed from the machine and the next, partially assembled box may be placed in position for the next cycle of operation.

FIGURES 7, 8, 9, and 10 show another embodiment of the machine, which is generally similar except that it is motor-driven and includes means for mechanically conveying the partially assembled boxes into proper position at the assembly station within the machine, and for conveying the fully assembled boxes out of the machine.

As may be seen in FIGURE 7, this motor-driven machine includes, in addition to the elements previously illustrated and described, an elongated bed assembly, generally designated B, which includes transverse members 126 and 128 adjacent opposite ends of the main machine frame, these members having projecting laterally therefrom short extension plates 130 which are bolted to the upper flanges of the horizontal framing members 6. As best shown in FIGURE 7, the transverse members 134 and 128 support a pair of longitudinal guide rails 136 and 144, the rail 136 being fixed, and its outer end, as shown in FIGURE 7, being supported on a transverse rod 138 whose ends are fixed in blocks 140 adjustably mounted on the upper ends of legs 142. The guide rail 144 is adjustable to and from the fixed rail 136 to accommodate boxes of different widths, having attached to its transversely extending forked supports 146 which are clamped in the desired position by bolts 148. Guide rail 144 is supported at its right-hand end, as viewed in FIGURE 7, by a short, depending leg 150 slidably mounted on the transverse rod 138. Secured to the under side of the two guide rails 136 and 144 adjacent their right-hand ends is a transverse member 134 having adjustably secured to its lower face a forked bracket 152 in whose free end is received a short stud 154 upon which a freely rotating sprocket 156 is secured endwise by a collar 158. As shown in FIGURES 7 and 8, at the outer end of the bed assembly B, the extension plates 130 support at their lower faces a pair of depending legs 160 which support the ends of a stationary transverse shaft 162 on which is rotatably mounted a sprocket 164. Trained about these two sprockets 156 and 164 is a conveyor chain 244 whose upper run is slidably supported in a shallow channel 132 (best shown in FIGURE 9) which rests upon the top of the transverse members 126, 128 and 134. This chain 244 is intermittently driven by the mechanism now to be described.

As may be seen in FIGURES 8 and 9, the machine includes a base framework comprised of a pair of spaced, longitudinally extending channel members 166 and 168 mounted on transverse members 170 and 172 which in

turn are bolted to the foot flanges of the aforementioned horizontal framing members 8. As shown in FIGURE 8, an intermediate transverse member 174 is fastened to the bottom faces of the channel members 166 and 168 to support the inner ends of two pairs of spaced bar members 176 (best shown in FIGURE 9) whose outer ends are supported on the upper face of the transverse member 172. These bar members 176 are spaced to provide adjustable support for an electric gear motor 178 which is clamped thereon by bolts 180.

As shown in FIGURE 8, the drive shaft of gear motor 178 has keyed thereon a sprocket 186 about which is trained a chain 184 which is also trained about a large diameter sprocket 188 keyed on the inner end of a drive shaft 182. Rotatably attached to the outer face of the latter sprocket 188 by a bolt 190 is the rod end 62 of the aforementioned connecting rod 60 whose upper end is connected to the shaft 55 of the actuator assembly. As best shown in FIGURE 9, the drive shaft 182 is journaled in bearings 192 mounted on the upper faces of the channel members 166 and 168 and has keyed upon it a crank 194 (FIGURE 8) which rotatably supports near its outer end a roller 196 which bears against the lower face of a cam plate 198 fastened to the inner face of an elongated arm 200 whose right-hand end, as viewed in FIGURE 8, is pivotally mounted on a stud 202 supported in the upper portion of the outer face of a plate 204 projecting upwardly from the outer face of the channel member 166.

As the drive shaft 182 rotates, in the direction indicated by the arrow A in FIGURES 7 and 8, the roller 196 moves in a circular path, and by engagement with the cam plate 198 imparts a vertical rocking motion to the arm 200. The outer end of the arm 200 is pivotally attached by a bolt 206 to a pawl rod 208, which is urged in a counterclockwise direction, as viewed in FIGURE 8, by a tension spring 210 one end of which is hooked about a stud 212 projecting from the inner face of pawl rod 208 and the other end of which is hooked about a stud 214 projecting from the inner face of arm 200. As best shown in FIGURES 9 and 10, the pawl rod 208 carries adjacent its upper end a stud 216 which projects outwardly from either side thereof and rides along hardened slide plates 242 extending inwardly from the edges of a pair of side plates 218 and 220, bolted near their upper and lower ends to the opposite ends of side plates 220 and 218, respectively. The upper spacing member 224 is bolted to the depending flange of the transverse frame member 6, while the lower end of the side plate 218 is secured to the outer face of the channel member 166.

Extending through the side plates 218 and 222 near their lower ends is a short shaft 226 which is journaled in bearings 228 secured to the outer faces of the side plates, this shaft 226 extending beyond the bearing on side plate 218 and having keyed thereon a sprocket 230, which is in alignment with the aforementioned sprocket 164 and which also has the conveyor chain 244 trained about it. Keyed to shaft 226 at a point substantially midway between the side plates 218 and 220 is a small diameter sprocket 232 aligned with another sprocket 234 of similar size which is rotatably supported on a stationary shaft 236 extending between the upper portions of side plates 218 and 220. A chain 238 trained about these sprockets 232 and 234 has mounted thereon at uniform intervals a series of ratchet blocks 240 which are slidably supported on vertical rails 241 fastened to the inner faces of the side plates 218 and 220 (FIGURE 10). These ratchet blocks 240 are positioned so that the slightly beveled upper end of the pawl rod 208 will contact their bottom faces during the upward strokes of the reciprocal motion of the pawl rod.

In FIGURES 8 and 10, the arm 200 and pawl rod 208 are shown in their lowermost position by full lines P₁. The length of the vertical strokes of the upper beveled end of the pawl rod slightly exceeds the spacing between the lower faces of the adjacent ratchet blocks 240 on

chain 238. This causes the pawl rod to advance the chain 238 stepwise in increments equal to said spacing and assures that the downward stroke of the pawl rod will carry it to a lower position, shown in the full lines P_1 in FIGURE 10, at which its beveled upper end is slightly below the next succeeding ratchet block 249 and in position to contact the bottom face of the latter block during the first portion of its next upward stroke to the upper position shown in broken lines P_2 .

These incremental advances of the chain 238 impart intermittent, counterclockwise rotation to shaft 226 and its attached sprocket 230, thereby also causing step-wise movement of the conveyor chain 244 through increments equal to the uniform spacing of a series of push blocks 246 thereon.

The spacing of these blocks 246 is slightly greater than the length of the boxes, and the blocks are provided with the beveled cap members 248 to facilitate placement of the boxes between the blocks for pushing of the boxes thereby into and out of the machine.

As will be understood from the foregoing description, energizing of the gear motor 178 imparts continuous clockwise rotation to drive shaft 182, thereby causing the box-squaring and loop-fastener-bending mechanism, generally designated L, as well as the arm 200 and pawl rod 208 to operate continuously in synchronism. Thus, the conveyor chain 244 will be driven stepwise, moving the boxes one by one into the box-assembly station opposite the continuously operating mechanism L which operates upon the box during the interval when it is stationary at said station, thereby squaring the box and closing its threaded loop fasteners. Then, as the mechanism L moves out of engagement with the assembled box, the conveyor chain 244 indexes another step to move the box out of machine and to move another partially assembled box into the box assembly station.

From the foregoing description, it will be apparent that the present invention provides a practical machine for completing the assembly of wirebound boxes at a rapid rate of production. However, it should be emphasized that the particular embodiments of the invention described herein and shown in the accompanying drawings are intended as merely illustrative of the principle of the invention, and not as restrictive of the scope thereof, which is limited only by the appended claims.

I claim:

1. A wirebound box assembling machine comprising a frame, a box support mounted on said frame for supporting partially assembled wirebound boxes for movement into and out of said machine, loop bending mechanism mounted on said frame for bending previously threaded fastener loops at a corner of a wirebound box in said machine, said loop bending mechanism including an actuator assembly mounted on said frame and being generally vertically movable toward and away from said corner, loop bending members pivotally mounted on said actuator assembly and having loop engaging portions which project downwardly in position to engage the outer loops adjacent said corner on downward movement of said actuator assembly, yieldable means resisting rotation of said loop bending member relative to said actuator assembly, said loop bending members having their edges adjacent said corner shaped to extend around said corner and their pivotal axes being located above the top of said box and inwardly of said corner, so that as said actuator assembly moves downwardly toward said corner, said loop engaging portions will engage the top of said box adjacent said corner, causing said loop bending members to be rotated relative to said actuator assembly against the resistance of said yieldable means through an arc having an upwardly directed vertical component and a horizontal component directed toward said corner whereby said loop engaging portions will move generally horizontally until they clear said corner, and then will move downwardly along the side of said box,

first bending said outer loops around said corner and then bending the inner loops around said outer loops and downwardly adjacent said side, and drive means for driving said actuator assembly.

5 2. A machine as described in claim 1 in which the surface of said loop bending members which engages said loops is inclined inwardly relative to said side of said box so that, as said inner loops are bent downwardly, they are also urged inwardly of the outside binding wires on said side.

10 3. A machine as described in claim 1 in which stop means are provided on said actuator assembly for engaging and adjustably limiting the relative pivotal movement of said loop bending members, whereby when said loop 15 engaging portions reach said corner of said box, said loop bending members simultaneously engage said stop means to stop their pivotal movement relative to said actuator assembly and, as said actuator assembly continues downwardly, said loop bending members are forced 20 downwardly in fixed relation with it.

4. A machine as described in claim 3 wherein said actuator assembly is pivotally mounted for arcuate movement about an axis located generally horizontally outward from and slightly below said corner whereby during the generally downward movement of said actuator 25 assembly and said loop bending members in fixed relation to one another, said loop bending members will move in paths having a slight, inwardly directed horizontal component, thereby bending said inner loops downwardly and inwardly against the front face of said box.

5. A machine as described in claim 1 in which said box support includes a pair of rollers rotatably mounted on axes extending transversely of the path of said boxes into and out of said machine, said rollers being spaced so that the ends of a box in an assembly station opposite said loop bending mechanism will fit between them with only slight clearance to allow the box to drop downwardly upon a supporting surface below the plane of the upper surfaces of said rollers, whereby said box is held against endwise movement at said assembly station.

40 6. A wirebound box assembling machine comprising a frame, a box support mounted on said frame for supporting partially assembled wirebound boxes for movement into and out of said machine, a box bracing member fixedly mounted on said frame at one side of said box support to engage and brace one side of a box supported thereon, box assembling mechanism mounted on said frame for bending previously threaded fastener loops at a corner of each of said wirebound boxes, said box 45 assembling mechanism including an actuator assembly mounted on said frame and being generally vertically movable toward and away from said corner, a box engaging member movably mounted on said frame at the side of said box support opposite said box bracing member, said box engaging member being mechanically coupled to said actuator assembly for movement in synchronism therewith, such movement of said box engaging member causing it to engage a side of a box on said box support and compress said box against said box bracing member to square said box and hold it in position for a loop bending operation, loop bending members pivotally mounted on said actuator assembly and having loop engaging portions which project downwardly 50 in position to engage the outer loops adjacent said corner on downward movement of said actuator assembly, yieldable means resisting rotation of said loop bending member relative to said actuator assembly, said loop bending members having their edges adjacent said corner shaped to extend around said corner and their pivotal axes being located above the top of said box and inwardly of said corner, so that as said actuator assembly moves downwardly toward said corner, said loop engaging portions will engage the top of said box adjacent said corner, 55 causing said loop bending members to be rotated relative to said actuator assembly against the resistance of said yieldable means through an arc having an upwardly directed vertical component and a horizontal component directed toward said corner whereby said loop engaging portions will move generally horizontally until they clear said corner, and then will move downwardly along the side of said box, 60 causing said loop bending members to be rotated relative to said actuator assembly against the resistance of said yieldable means through an arc having an upwardly directed vertical component and a horizontal component directed toward said corner whereby said loop engaging portions will move generally horizontally until they clear said corner, and then will move downwardly along the side of said box, 65 causing said loop bending members to be rotated relative to said actuator assembly against the resistance of said yieldable means through an arc having an upwardly directed vertical component and a horizontal component directed toward said corner whereby said loop engaging portions will move generally horizontally until they clear said corner, and then will move downwardly along the side of said box, 70 causing said loop bending members to be rotated relative to said actuator assembly against the resistance of said yieldable means through an arc having an upwardly directed vertical component and a horizontal component directed toward said corner whereby said loop engaging portions will move generally horizontally until they clear said corner, and then will engage the top of said box adjacent said corner,

causing said loop bending members to be rotated relative to said actuator assembly against the resistance of said yieldable means through an arc having an upwardly directed vertical component and a horizontal component directed toward said corner, whereby said loop engaging portions will move first generally horizontally until they clear said corner and then downwardly along the side of said box, first bending said outer loops around said corner and then bending the inner loops around said outer loops and downwardly adjacent said side, and drive means for driving said actuator assembly.
